UNITED STATES PATENT OFFICE.

ARMAND H. PEYCKE, OF CHICAGO, ILLINOIS, ASSIGNOR TO AMERICAN STEEL
FOUNDRIES, OF CHICAGO, ILLINOIS, A CORPORATION OF NEW JERSEY.

BRAKE-SUPPORTING MEANS.

1,315,395.

Specification of Letters Patent. Patented Sept. 9, 1919.

Application filed February 13, 1918. Serial No. 217,003.

To all whom it may concern:

Be it known that I, ARMAND H. PEYCKE, a citizen of the United States, and resident of Chicago, in the county of Cook and State 5 of Illinois, have invented certain new and useful Improvements in Brake-Supporting Means, of which the following is a specification.

This invention relates to brake supporting 10 means.

One of the objects of this invention is to make it possible to readily adjust the leveling means for brake beams.

Another object of the invention is to provide an adjustable brake beam leveling and supporting means adapted to meet the various requirements for successful commercial 15 operation.

Generally speaking, these and other objects are accomplished by providing in combination, a brake beam, a safety bar underlying the same, and means adjustably connected to one and operatively connected to the other for supporting the brake beam.

The invention is illustrated on the accompanying sheet of drawings in which,

Figure 1 is a fragmentary side elevation, parts being in section, of a railway car truck, embodying my invention.

Fig. 2 is a fragmentary side elevation on an enlarged scale, parts being in section, of the brake beam supporting and leveling arrangement.

Fig. 3 is a fragmentary end elevation of 30 the arrangement shown in Fig. 2, and

Fig. 4 is a side elevation, parts being in section of brake beam supporting and leveling means and being slightly modified from the arrangement shown in Fig. 2.

The various novel features of the invention will be apparent from the following description and drawings and will be particularly pointed out in the appended claims.

Referring to the figures of the drawing, 40 it will be noted I have shown a railway car truck, including a spring plank 10 to which are secured vertically arranged hangers 11, provided with a plurality of apertures 12, for the reception of a horizontally extending rigid safety bar 13, the ends of which underlie brake beams 14. The main function of this rigid safety bar is to prevent the brake beams from falling to the tracks if the same become detached from their normal 45 hangings.

Mounted upon each end of the safety bar 13 is a looped resilient member 15, the ends of which 16 and 17 are provided with a plurality of apertures 18 for the reception of the ends of the safety bar 13. In other 60 words, the resilient members 15 are slipped onto the ends of the safety bar 13 and locked thereto preferably by spring clips 19, which not only lock the resilient members 15 on the bar 13, but also lock the bar with respect to 65 the hangers 11, normally to prevent movement of the safety bar 13. The middle part 20 of the resilient member 15 is upwardly inclined toward the wheels of the truck and is embraced by a collar member 21, which is 70 slidably mounted upon the portion 20 of the resilient member 15. This collar 21 is provided with an opening for the reception of the tension member 22, of the brake beam, it being understood that the arrangement 75 described is duplicated on each side of the truck.

During the application and release of the brakes, it is apparent that there will be a sliding movement of the beam relative to 80 the resilient member 15, the collar on the tension member sliding on the intermediate portion 20 of the resilient member 15. This resilient member also permits a vertical movement in accordance with operating conditions.

To maintain the brake beams at the proper level and to properly guide the brake shoes into engagement with the wheels, the ends of the resilient members 15 have been apertured as hereinabove stated, whereby either one end of the resilient member 15 or both ends thereof may be raised or lowered in accordance with requirements to give the proper tilt or position of the beams. If the 90 resilient member or leveling device 15, is at the proper inclination, but is too high or too low, the position of the safety bar 13 may be raised or lowered to make the adjustment without changing the adjustment of the 95 resilient members 15. In this way the leveling devices and therefore the beams may be adjusted to a nicety.

Referring particularly to Fig. 2, it will be noted that the end of the safety bar 13 is cut at an angle, thereby removing a portion of the lower flange 23 and exposing a narrowed portion 24 of the upper flange. While both ends of the resilient member 15 are apertured, it will be noted that the outer end 16 110

has its apertures formed by struck up portions 25, of metal, which engage the narrowed flange portion 24 and hold the leveling device in adjusted position. By narrowing the flange at 24 a finer adjustment may be obtained. By tapering off the end of the safety bar 13, adjustment of the leveling device also is greatly facilitated.

The arrangement shown in Fig. 4 is substantially the same as that shown in Fig. 2 with the exception that only the outer end of the resilient member 15 is made adjustable with respect to the safety bar.

It is my intention to cover all modifications of my invention, which fall within the spirit and scope of the following claims.

I claim:

1. In combination, a brake beam, a safety member underlying the same, and means adjustably and releasably connected to one and operatively connected to the other for supporting the brake beam, said means being adjustable in a vertical direction.
2. In combination, a brake beam, a safety member underlying the same, and means adjustably and releasably connected to the safety member and operatively connected to the brake beam for supporting the latter, said means being adjustable in a direction to change the position of the brake beam.
3. In combination, a brake beam, a safety member therefor, and resilient means adjustably and releasably connected to said safety member and being slidably associated with said beam, said resilient means being removable from said safety member by a longitudinal movement.
4. In combination, a brake beam, a safety bar therefor, and a member for supporting said brake beam and having one end adjustably connected to the safety bar for varying the effective height of a portion of the brake beam.
5. In combination, a brake beam, a safety bar therefor, and a member for supporting

said brake beam and having its ends adjustably connected to the safety bar.

6. In combination, a brake beam, a safety bar therefor, and a looped resilient member having its ends connected to the safety bar and having an intermediate portion slidably associated with the brake beam, one end of the resilient member being adjustable with respect to the bar for leveling the beam.

7. In combination, a brake beam, a safety bar therefor, and a resilient supporting member for the brake beam, having its ends provided with series of apertures whereby the resilient member may be adjustably mounted on the safety bar.

8. In combination, a brake beam, a safety bar operatively associated with the beam, and a support for adjustably receiving the safety bar for leveling the beam.

9. In combination, a brake beam, a safety bar therefor, means operatively connecting the safety bar and brake beam, and a support in which the safety bar may be adjustably mounted for leveling the brake beam.

10. In combination, a brake beam, a safety bar therefor, a member adjustably connected to the safety bar and operatively connected to the brake beam for leveling the latter, and a support in which the safety bar is adjustably mounted also for leveling the beam.

11. In combination, a brake beam, a safety bar underlying said brake beam, a resilient member operatively connected with the brake beam and having a plurality of apertures whereby said member may be adjustably connected to the safety bar for leveling the brake beam, and an apertured support in which the safety bar may be adjustably mounted for leveling the brake beam.

Signed at Chicago, Illinois, this 26th day of January, A. D. 1918.

ARMAND H. PEYCKE.
